CLAIM

I claim the ornamental design for a case for mobile communications device, as shown and described.

DESCRIPTION

FIG. 1 is a front perspective view of a case for mobile communications device showing my new design;

FIG. 2 is a rear perspective view of the case for mobile communications device of FIG. 1;

FIG. 3 is a front view of the case for mobile communications device of FIG. 1;

FIG. 4 is a rear view of the case for mobile communications device of FIG. 1;

FIG. 5 is a left-side view of the case for mobile communications device of FIG. 1;

FIG. 6 is a right-side view of the case for mobile communications device of FIG. 1;

FIG. 7 is a top view of the case for mobile communications device of FIG. 1; and,

FIG. 8 is a bottom view of the case for mobile communications device of FIG. 1.

1 Claim, 6 Drawing Sheets
